UNITED STATES PATENT OFFICE.

WALTER THOMAS HALL AND WILLIAM JOSEPH BAYLISS, OF LONDON,
ENGLAND.

DRAFT-EXCLUDER FOR DOORS.

SPECIFICATION forming part of Letters Patent No. 543,932, dated August 6, 1895.

Application filed November 5, 1894. Serial No. 527,935. (No model.)

To all whom it may concern:

Be it known that we, WALTER THOMAS HALL, salesman, residing at 54 South Island Place, Stockwell, and WILLIAM JOSEPH BAYLISS, builder's clerk, residing at 5 Great Quebec Street, Marylebone, London, England, subjects of the Queen of Great Britain and Ireland, have invented certain new and useful Improvements in Draft-Excluders for Doors, Windows, and the Like, of which the following is a specification.

This invention relates to an improved draft-excluder, and is intended to provide a very simple and inexpensive form which can be easily applied.

In carrying out our invention we employ a length of chenille which is formed of a plush-like pile round a central wire or wires, the pile being usually engaged between two twisted wires. This chenille is inclosed in a tube of cloth, baize, or other suitable material, preferably stitched round it. The complete article is then fixed in the rabbet or angle of the door-frame, either by adhesive material or by small tacks.

In order that the invention may be more clearly understood, reference is had to the accompanying sheet of drawings, in which—

Figures 1 and 2 show the draft-excluder fixed in place. Fig. 3 is a side elevation of a length of the article with a portion of the chenille projecting, and Fig. 4 is a cross-section.

A is the chenille formed in the manner

above described, inclosed in the tube, which 35 is of baize or other material formed by bending a strip round the chenille and stitching it at the side, as shown in Figs. 1 and 2. The draft-excluder is fixed in the rabbet of the door, so that the edge of the latter will press 40 against it when closed. As used for windows, it is fixed in a corresponding position pressing against the edge of the sash.

The side b at which the tube B is stitched may be extended to form a flange for greater 45 convenience in fixing. This is especially useful if the draft-excluder is to be fixed by tacks.

The excluder may also be fixed to a small band which is fitted in place on the door-frame or window.

What we claim as our invention, and desire to secure by Letters Patent, is—

An improved draft excluder for windows, doors and the like, formed from a length of 55 chenille inclosed in a tube of baize, cloth or the like material, and fixed in the rabbet of the door frame or corresponding part of the window, substantially as and for the purposes specified.

In witness whereof we have hereunto set our hands in the presence of two witnesses.

WALTER THOMAS HALL.
WILLIAM JOSEPH BAYLISS.

In presence of—
FRANK WILLIAM PATTISON,
ALBERT EDWARD ELLEN.
